UNITED STATES PATENT OFFICE

115,158

DESIGN FOR A FLUORESCENT TUBE SOCKET CROWN

Frederick K. Maerz, New York, N. Y., assignor
to Harry J. Gruber and Max D. Gruber, doing
business as Gruber Bros., New York, N. Y.

Application February 13, 1939, Serial No. 82,953

Term of patent 3½ years

To all whom it may concern:

Be it known that I, Frederick K. Maerz, a citizen of the United States and a resident of the city of New York, in the county of Queens and State of New York, have invented a new, original, and ornamental Design for a Fluorescent Tube Socket Crown, of which the following is a specification, reference being had to the accompanying drawing constituting a part thereof.

Fig. 1 is a top plan view of a fluorescent tube socket crown showing my new design.

Fig. 2 is a side elevational view of my socket crown as shown in Fig. 1.

Fig. 3 is a perspective view thereof.

I claim:

The ornamental design for a fluorescent tube socket crown, substantially as shown.

FREDERICK K. MAERZ.
